UNITED STATES PATENT OFFICE.

WILLIAM E. CAIN, OF NEWARK, NEW JERSEY.

DESIGN FOR A BRASSIÈRE.

45,853.

Specification for Design.

Patented June 2, 1914.

Application filed March 30, 1914. Serial No. 828,410. Term of patent 3½ years.

To all whom it may concern:

Be it known that I, WILLIAM E. CAIN, a citizen of the United States, residing in Newark, Essex county, and State of New Jersey, have invented a new, original, and ornamental Design for a Brassière, as illustrated in the accompanying drawing, of which the following is a specification.

The drawing herewith illustrates in perspective a brassière, in which my novel de-

sign is embodied, and such illustration will render the same so clear as to cause any detail description thereof unnecessary.

I claim:

The ornamental design for a brassière, as shown.

WILLIAM E. CAIN.
